ROBERT A. RUSSELL, OF NEW YORK, N. Y.

CLOSURE FOR RECEPTACLES.

1,272,859.

Specification of Letters Patent. Patented July 16, 1918.

Application filed November 27, 1915. Serial No. 63,702.

To all whom it may concern:

Be it known that I, ROBERT A. RUSSELL, residing at New York, in the county of New York and State of New York, have invented 5 certain new and useful Improvements in Closures for Receptacles, of which the following is a specification.

This invention relates to a closure for receptacles, and particularly to a closure for 10 bottles, such as are commonly used for containing catchup and the like.

The principal object of the invention is to provide a closure which is attractive, simple and efficient.

15 A more particular object is to provide a closure comprising a cover part and a tubular part, the cover part being adapted to overlie the opening in the bottle neck and the tubular part being adapted to encircle 20 the exterior walls of the bottle neck and having means to draw down the cover part tightly into sealing engagement with the upper end of the bottle neck, and to provide means interengaging between the closure 25 and the bottle adapted to prevent accidental loosening of the cover part from sealing engagement.

A further object is to provide a closure 30 having a threaded part for engaging the bottle neck, and to provide a sleeve associated therewith for gripping a portion of the bottle neck to prevent detachment of the tubular part, the sleeve preferably possessing the quality of losing its grip upon the 35 bottle when the tubular part is forcefully rotated and thereby moved upwardly owing to the engagement of its threads with the threaded surface of the bottle, and said sleeve further preferably possessing the 40 quality of indicating by its condition any unwarranted tampering with the closure.

A further object is to make the sleeve 45 above referred to as a separate member, if desired, so that it may be removed without interfering with the use of the remainder of the closure as a temporary sealing means.

Other objects and aims of the invention, 50 more or less specific than those referred to above, will be in part obvious and in part pointed out in the course of the following description of the elements, combinations,

arrangements of parts and applications of principles, constituting the invention; and the scope of protection contemplated will be indicated in the appended claims.

55

In the accompanying drawings which are to be taken as a part of this specification, and in which I have shown a merely preferred form of embodiment of the invention:

Figure 1 represents a vertical central sectional view through a closure constructed in accordance with the provisions of this invention.

Figure 2 represents a similar view illustrating a modification.

65

Figure 3 represents a top plan view of the structure shown in Fig. 1.

Figure 4 represents a top plan view of the structure shown in Fig. 2; and

Figs. 5 and 6 illustrate further modifications.

Referring to the drawings for a detailed description of the structure shown therein, the reference character L indicates the cover part of the closure, G the tubular part, and 75 H the sleeve. These parts are each preferably formed of sheet metal, such as tin or the like, preferably lacquered upon all its surfaces so as to avoid corrosion in cases where the metal itself is subject thereto.

80

The cover part comprises a disk of a size to cover the upper end of the bottle neck. Its exterior surface may be ornamented in any desired manner, as by embossing or lithographing.

85

The tubular part is preferably made as a sheet of metal bent around into tubular form and seamed together at its edges as indicated at 1 in Fig. 3. The upper annular edge of the tubular part may be connected to the peripheral portion of the cover part in any manner, but is preferably connected by means of a seam, as shown at 2. The form of the seam, so far as the present invention is concerned, is immaterial, except that an 95 advantage results in so forming the seam that a portion thereof projects above the exterior surface of the cover part so as to serve as a protecting ridge about the ornamentation which may be carried upon the 100 outer surface of the cover part, and except also that an advantage is provided by mak-

ing the inner annular portion of the cover part bent slightly downwardly where the seam is formed so as to provide a part adapted to hug more closely about the upper 5 annular edge of the bottle, as is clearly shown at 3 in Fig. 1. The tubular part is preferably pressed so as to form threads 4 thereon adapted to engage corresponding threads 5 formed upon the bottle neck in a 10 manner common to closures of this type.

A lining member or gasket 6 is arranged within the closure against the inner surface of the cover part.

By rotating the tubular part downwardly 15 about the threaded surface of the bottle, the lining member 6 is brought into engagement with the upper surface of the bottle neck. A little force applied in rotating the tubular part downwardly causes the member 6 to 20 constitute an effective seal for the opening in the bottle neck.

The sleeve H is designed primarily to prevent any rotation of the tubular part from a position in which it holds the member 25 6 in tight sealing engagement. This sleeve preferably comprises a strip of metal bent around the lower annular edge of the tubular part and connected thereto as by a seam 7. It may, however, be formed integrally with the tubular part if expedience so dictates. Prior to screwing the tubular part down upon the bottle neck the lower 30 annular edge of the sleeve projects straight downward as indicated by the dotted lines in Fig. 1. After the tubular part has been screwed home then the lower annular edge of the sleeve is bent inwardly, as at 8, so as to engage firmly beneath the under surface 35 of an annular bead 9 formed upon the bottle 40 neck.

The firmness with which the portion 8 grips the bead depends upon the extent to which it projects beneath the bead, to the shape of the under surface of the bead, and 45 to the stiffness of the material of which the sleeve is composed. Preferably these elements are arranged so that the sleeve will constitute a grip which is amply sufficient to retain the tubular part against any rotation under all ordinary, or even slightly 50 excessive, conditions. When, however, a highly excessive force is applied to rotate the tubular part, then the grip of the sleeve will loosen, the part 8 will be caused to bend 55 outwardly, and the closure will thereafter be easily removable.

In case the closure has been loosened by unauthorized hands, the condition of the sleeve after having been once removed as 60 above, will serve as an efficient indication that the closure has been tampered with.

In the modification, Fig. 2, the sleeve is not only formed as a separate member, but

it is so shaped as to be easily detachable from the remainder of the closure after the bottle 65 has been once opened.

In Fig. 2 also the parts L and G are shown integral with each other. In this instance the sleeve may be made without a seam, as shown in Fig. 4. A seamless sleeve of this 70 nature may be also employed in connection with cover and tubular parts which are seamed together as in Fig. 1, such an arrangement being shown in Fig. 6. A structure in which the cover and tubular parts are 75 seamless, and in which the sleeve is formed of a band of metal seamed together is shown in Fig. 5. Such structure is preferably employed in connection with a seam such as shown at 7 in Fig. 1.

It will be understood that various changes may be made in the form, construction and arrangement of the several parts and hence I do not intend to be limited to the details herein shown and described, except as they 85 may be specifically included in the claims.

Having thus described my invention what I claim as new and desire to secure by Letters Patent is:

1. A screw closure comprising, a threaded body portion adapted for coöperative engagement with a threaded receptacle for drawing the closure into sealing engagement therewith, and a bendable sleeve depending from the lower part of the body portion and rotatable with respect thereto, said sleeve being adapted to be crimped about a beading on the receptacle for normally holding the closure in sealing position, whereby the forcible unscrewing of the closure will break the engagement of the sleeve with the beading and permit the removal of the closure.

2. A screw closure comprising, a threaded body portion adapted for coöperative engagement with a threaded receptacle for drawing the closure into sealing engagement therewith, and a removable bendable sleeve depending from the lower part of the body portion and rotatable with respect thereto, said sleeve being adapted to be crimped about a beading on the receptacle for normally holding the closure in sealing position, whereby the forcible unscrewing of the closure will break the engagement of the sleeve with the beading and permit the removal of the closure.

3. A screw closure comprising, a threaded body portion adapted for coöperative engagement with a threaded receptacle for drawing the closure into sealing engagement therewith, said body portion having its lower edge turned upwardly, and a bendable sleeve having its upper edge turned downwardly for rotatable engagement with the 125 upturned edge of the body portion, said

sleeve being adapted to be crimped about a beading on the receptacle for normally holding the closure in sealing position, whereby the forcible unscrewing of the closure will
5 break the engagement of the sleeve with the beading and permit the removal of the closure.

In testimony whereof I affix my signature in the presence of two witnesses.

ROBERT A. RUSSELL.
